[57] CLAIM

The ornamental design for a control unit of programmable controller, as shown and described.

DESCRIPTION

FIG. 1 is a front elevational view of the control unit of programmable controller showing my new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof; and

FIG. 7 is a perspective view thereof from a front upper left position.
